DESIGN FOR AN ARM ATTACHMENT FOR A GAUGE

Peter P. Followay, Forest Park, Ill.

Application November 26, 1945, Serial No. 124,084

Term of patent 14 years

(Cl. D52—1)

To all whom it may concern:

Be it known that I, Peter P. Followay, a citizen of the United States, residing in Forest Park, in the county of Cook and the State of Illinois, have invented a new, original, and ornamental Design for an Arm Attachment for a Gauge, of which the following is a specification, reference being had to the accompanying drawing, forming part thereof, in which:

Fig. 1 is a side elevational view of an arm attachment for a gauge showing my new design;

Fig. 2 is a side elevational view of the arm

attachment depicted in Fig. 1 taken on the opposite side to that shown in Fig. 1;

Fig. 3 is an end elevational view of the arm attachment depicted in Fig. 1;

Fig. 4 is a top plan view; and

Fig. 5 is an end elevational view of the arm attachment depicted in Fig. 1 taken on the opposite end to that shown in Fig. 3.

I claim:

The ornamental design for an arm attachment for a gauge, substantially as shown.

PETER P. FOLLOWAY.
